United States Patent Office

Des. 189,291
Patented Nov. 22, 1960

189,291

HAND TRUCK

Houghton W. Clarke, Wonder Lake, Ill., assignor to Meatpack Corporation, Evanston, Ill., a corporation of Illinois

Filed July 13, 1959, Ser. No. 56,754

Term of patent 14 years

(Cl. D14—3)

Fig. 1 is a perspective view of a hand truck embodying my new design;

Fig. 2 is a top plan view of the hand truck;

Fig. 3 is a side elevational view; and

Fig. 4 is an end elevation of the hand truck.

I claim:

The ornamental design for a hand truck, as shown.
